UNITED STATES PATENT OFFICE.

FRANK STEBBING, OF CHICAGO, ILLINOIS.

LIFE-PRESERVER.

1,297,270.

Specification of Letters Patent. Patented Mar. 11, 1919.

Application filed June 18, 1918. Serial No. 240,604.

To all whom it may concern:

Be it known that I, FRANK STEBBING, a citizen of the United States, residing at Chicago, in the county of Cook and State of Illinois, have invented new and useful Improvements in Life-Preservers, of which the following is a specification.

This invention relates to new and useful improvements in life preservers and the 10 principal object of the invention is to provide a device of this nature which will sustain the head of the wearer above the water even though the person may be unconscious or helpless from wounds or injuries.

Another object of the invention is to provide the life preserver with a ring which is adapted to encircle the neck of the wearer, and to come well up on his head when inflated, with means for making the device 15 conform to the physique of the person on which it is placed.

Another object of the invention is to provide means for restricting the inflation of the lower part of the device, thus preventing 20 this part from counter-acting the buoyancy of the collar.

Another object of the invention is to provide a device of this character which is simple and durable in construction, reliable and 25 efficient in operation and one which can be manufactured and placed upon the market at a minimum cost.

The invention also consists in certain other features of construction and in the combination and arrangement of the several parts, to be hereinafter fully described, illustrated 30 in the accompanying drawings and specifically pointed out in the appended claims.

In describing my invention in detail, reference will be had to the accompanying 40 drawings wherein like characters denote like or corresponding parts throughout the several views, and in which:—

Figure 1 is a view showing the invention 45 in use.

Fig. 2 is a like view with the device shown in section.

Fig. 3 is rear view of the preserver.

Fig. 4 is an edge view.

Fig. 5 is a section on line 5—5 of Fig. 3.

Fig. 6 is a section on line 6—6 of Fig. 3.

Fig. 7 is a like view with the device partly deflated.

Fig. 8 shows the device in folded-up position.

Fig. 9 shows a carrying case for the device.

As shown in these views 1 indicates the preserver which consists of the collar part 2 and the front and rear aprons 3. As 60 shown, the collar 2 is formed of front and rear portions suitably connected together at their ends at the sides of the device. These sides are inclined, as shown, so that the collar is of frusto-conical shape. The aprons 65 are of substantially V-shape and it will be seen that the said aprons are formed from continuations of the two portions of the collar. The front and rear portions of each apron at each side thereof immediately below the collar are cemented together as at 70 4. These cemented portions are of substantially V-shape with the base of the V at the outer edges of the aprons.

Reinforcing strips 5 are cemented to the 75 interior faces of the device around said cemented portions, as clearly shown in Fig. 5. As will be seen these cemented portions are located in front and rear of each shoulder so as to make the collar conform to the physique of the wearer.

A reinforcing tab 6 is placed at the point where the edges of the aprons connect with the lower edge of the collar at the shoulder portion. Of course, it will be understood 80 85 that these reinforcing pieces may be placed whereever desired or found necessary.

The front and rear portions of each of the aprons are connected together centrally by webbing 7. I prefer to use two strips 90 of this webbing as shown in Fig. 6, and of elongated form as shown in Fig. 3. By this means the inflation of the aprons is restricted so that the same will not interfere with the action of the collar. An adjustable 95 strap 8 is connected with the end of one apron and a ring 9 is connected with the end of the other apron. This ring is engaged by a snap hook or the like 10 carried by the strap 8.

A tube 11 is connected with the interior of the collar and its outer end is provided with a suitable valve 12. I prefer to connect this tube with the rear part of the collar and to make it sufficiently long to reach the 105 mouth of the wearer so that he may readily inflate the device by blowing into the tube.

The device is placed over the head with the aprons in front and rear. The strap is passed between the legs and adjusted to 110

firmly hold the aprons against the body. When the device is inflated the collar will closely fit the neck, beginning at a point at the shoulders and coming well up on the head. In this way the head will be held in its highest position and will be prevented from drooping on the neck. The webbing will cause the aprons to assume a substantially tapered form so as to act with the collar in holding the body in a perpendicular position while in the water.

When the device is not in use it may be folded into the position shown in Fig. 8 and it may be carried in a suitable case such as 15 that shown at 13 in Fig. 9.

It is thought from the foregoing description that the advantages and novel features of my invention will be readily apparent.

I desire it to be understood that I may 20 make changes in the construction and in the combination and arrangement of the several parts, provided that such changes fall within the scope of the appended claims.

What I claim is:—

25 1. A life preserver comprising a continuous collar of substantially frusto-conical shape forming an upper air compartment,

front and rear aprons of V shape depended from the front and rear of said collar, each apron having front and rear walls connected together at their edges to form an air compartment which is in communication with the upper compartment, attaching means at the lower ends of the aprons, webbing connecting the central portions of the 35 interior walls of each of said aprons together and an inflation tube carried by the collar.

2. A life preserver comprising a continuous collar forming an upper air compartment, front and rear aprons of V shape depending from the front and rear of said collar, each apron having front and rear parts connected together at their edges to form air compartments which are in communication with the upper air compartment, 40 webbing connecting the central parts of the front and rear interior walls of each apron together, and each apron having the edge portions of the front and rear interior walls connected together immediately below said 45 collar and an inflation tube carried by said collar.

In testimony whereof I affix my signature.
FRANK STEBBING.
